[57] CLAIM

The ornamental design for a giftbox greeting card, as shown and described.

DESCRIPTION

FIG. 1 is a top plan view showing my new design;

FIG. 2 is a right side elevational view thereof;

FIG. 3 is a front end elevational view thereof;

FIG. 4 is a rear end elevational view thereof;

FIG. 5 is a left side elevational view thereof;

FIG. 6 is a bottom plan view thereof; and,

FIG. 7 is a view in perspective showing the device in opened condition.

The broken lines shown in FIGS. 1 and 7 are for illustrative purposes only, forming no part of the claimed design.

FIG. 1

FIG. 2

FIG. 3

FIG. 4
